CLAIM

The ornamental design for a cartridge, as shown and described.

DESCRIPTION

FIG. 1 is a top front perspective view of a cartridge showing the new design;

FIG. 2 is a bottom rear perspective view thereof;

FIG. 3 is a front view thereof;

FIG. 4 is a rear view thereof;

FIG. 5 is a left view thereof;

FIG. 6 is right view thereof.

(Continued)

FIG. 7 is a top view thereof; and,
FIG. 8 is a bottom view thereof.
The broken lines shown in the Figures depict portions of the
cartridge that form no part of the claimed design.

1 Claim, 4 Drawing Sheets
